RAG GUARD FOR POSITIVE DISPLACEMENT PUMPS

Leonard M. Nechine, Highland Park, Ill., assignor to FMC Corporation, a corporation of Delaware
Filed Oct. 23, 1959, Ser. No. 848,447
6 Claims. (Cl. 103—117)

This invention relates to a rag guard for positive displacement pumps particularly adapted to prevent rags and stringy material entering the suction chamber from being wrapped around the rotating drive shaft.

The present invention will be described with reference to a pump suitable for sludge pumping in which a rotating drive shaft is connected to one end of a rotor by a universal joint located in the suction chamber of the pump. In pumps of this type rags and stringy material entering the suction chamber have a tendency to be wrapped around the exposed portion of the drive shaft or the universal joint so as to impair the efficiency of the pump.

The rag guard comprises a flexible member, preferably rubber, in the shape of a truncated cone having one end held between the flanges of the suction chamber and the packing box flange. The smaller end of the rag guard bears on a smooth surface of the rotor adjacent the universal joint. The rag guard is apertured to equalize the pressure on both sides so that it will not be forced out of position by pressure differential. The rag guard is molded with an expansion fold adjacent its large end so that the circular motion of the rotor will not cause displacement of the small end of the rag guard.

The stationary surface of the rag guard causes rags and stringy material entering the suction chamber to flow directly into the opening of the pumping area between rotor and stator so that they are carried to the discharge end of the pump without interfering with the operation of the pump.

The structure by means of which the above-mentioned and other advantages of the invention are attained will be fully described in the following specification, taken in conjunction with the accompanying drawings showing a preferred illustrative embodiment of the invention, in which:

FIG. 1 is a fragmentary longitudinal sectional view of a pump provided with a rag guard embodying the invention;

FIG. 2 is an enlarged fragmentary longitudinal sectional view of the rag guard; and

FIG. 3 is a cross sectional view, taken along the line 3—3 of FIG. 2.

As shown in FIG. 1, the pump comprises a centrally disposed suction chamber 2 connected at one end to a housing 3 in which a drive shaft 4 is mounted, and at its other end to a housing 5 leading to a discharge outlet 6. Standards 7 of any suitable construction support the pump in horizontal position. Housing 3 includes a packing box 8 having an annular flange 9 secured to flange 10 of suction chamber 2 by bolts 11. A sleeve 12 rotatably mounted in one end of housing 3 is provided with end thrust bearings 13 near its outer end and bearings 14 near its inner end.

The opposite ends 15 and 16 of drive shaft 4 are tapered. A compressible gasket 17 provides a seal between end 15 of drive shaft 4 and the inner surface of sleeve 12. End 15 is provided with a transverse opening 18 the sides of which taper outwardly slightly from the center. A pin 19 extends through opening 18 and aligned openings 20 in sleeve 12. The ends of pin 19 are threaded into openings 21 in a ring 22 to provide a universal joint for holding end 15 of drive shaft 4 so

2

that it is rotated and oscillated by the rotation of sleeve 12 which is operatively connected to one end of the drive shaft of a motor (not shown).

End 16 of drive shaft 4 fits into a recess 23 in one end of a rotor 24. A compressible gasket 25 provides a seal between end 16 of drive shaft 4 and recess 23. End 16 is also provided with a transverse opening 26 tapered in the same manner as opening 18. A pin 27 extending through opening 26 and aligned openings 28 in the end of rotor 24 is secured in place by a ring 29 extending around the outer periphery of the adjacent end portion of rotor 24 and rigidly secured thereto in any suitable manner.

A stator 30 in housing 5 is provided with undulating surfaces 31, and rotor 24 is shaped in complementary manner to surfaces 31. As the rotor is rotated and moved with the circulatory movement imparted thereto by the rotation and oscillation of drive shaft 4, spaces 32, between the outer surface of the rotor and the inner surface of stator 30, are progressively moved outwardly from suction chamber 2 to discharge outlet 6. The rotor acts as a screw to move the material entering the suction chamber through an inlet 33 through housing 5 toward discharge outlet 6. Sludge is moved through the pump without difficulty, but rags and stringy material have a tendency to become wrapped around the drive shaft and thereby impair the efficiency of the pump.

A rag guard 34 of any suitable flexible material, preferably rubber, is secured at one end by an annular flange 35 clamped between flanges 9 and 10. The opposite end 36 of the rag guard, which is of increased thickness, is positioned on the outer surface of ring 29. The circulatory motion of ring 29 with the adjacent end of rotor 24 has a tendency to distort the rag guard transversely. In order to permit the rag guard to move freely and avoid slipping off the ring 29, an annular fold 37 is provided in the rag guard adjacent flange 35. The rag guard is provided with a plurality of apertures 38 that permit liquid in the suction chamber to pass therethrough so that the pressure inside the rag guard is the same as the pressure in the suction chamber outside the rag guard. Apertures 38 are small enough to prevent passage of rags or stringy material therethrough, and such material is carried by the inflowing liquid directly to the opening of the pumping area between rotor 24 and stator 30.

Although I have described a preferred embodiment of the invention in considerable detail it will be understood that the description thereof is intended to be illustrative, rather than restrictive, as many details of construction may be modified or changed without departing from the spirit or scope of the invention. Accordingly, I do not desire to be restricted to the exact structure disclosed.

I claim:

1. In combination with a pump having a housing forming a suction chamber, a drive shaft having one end positioned in said suction chamber, and a rotor having one end secured to said one end of said drive shaft, a flexible tubular rag guard enclosing the connection between said rotor and said drive shaft, said rag guard having apertures providing passageways for liquid from said suction chamber to the space enclosed by said rag guard to equalize the pressure within said rag guard and said suction chamber, said apertures being too small to admit rags into the space enclosed by said rag guard, one end of said rag guard slidably engaging the connection between said rotor and said drive shaft, and the other end of said rag guard being fixed relative to said housing.

2. A pump comprising a housing forming a suction chamber, a rotor having one end extending into said suction chamber, a drive shaft having one end connected to

said one end of the rotor, and a flexible tubular rag guard enclosing the connection between said drive shaft and rotor, said rag guard having one end fixed relative to said housing, the other end of said rag guard moving in a circular path with said rotor and said one end of the drive shaft, said one end of the rotor and said one end of the drive shaft rotating within a portion of said rag guard adjacent the last mentioned end of said rag guard, said rag guard having a plurality of apertures too small to permit rags to pass therethrough, said apertures providing passageways for liquid from said suction chamber to equalize the pressure within the space enclosed by said rag guard and the rest of the suction chamber.

3. A pump comprising a housing forming a suction chamber, a rotor having one end extending into said suction chamber, a drive shaft having one end connected to said one end of the rotor, and a flexible tubular rag guard enclosing the connection between said drive shaft and rotor, said rag guard having one end fixed relative to said housing, the other end of said rag guard moving in a circular path with said rotor and said one end of the drive shaft, said one end of the rotor and said one end of the drive shaft rotating within a portion of said rag guard adjacent the last mentioned end of said rag guard, said rag guard having an annular fold adjacent said first mentioned end to prevent displacement of said rag guard relative to said rotor as said last mentioned end moves in said circular path with said rotor and drive shaft.

4. A pump comprising a housing forming a suction chamber, a rotor having one end extending into said suction chamber, a drive shaft having one end connected to said one end of the rotor, and a flexible tubular rag guard enclosing the connection between said drive shaft and rotor, said rag guard having one end fixed relative to said housing, the other end of said rag guard moving in a circular path with said rotor and said one end of the drive shaft, said one end of the rotor and said one end of the drive shaft rotating within a portion of said rag guard adjacent the last mentioned end of said rag guard, said rag guard having a plurality of apertures too small to permit rags to pass therethrough, said apertures providing passageways for liquid from said suction chamber to equalize the pressure within the space enclosed by said rag guard and the rest of the suction chamber, said rag guard having an annular fold adjacent said first mentioned end to prevent displacement of said rag guard relative to said rotor as said last mentioned end moves in said circular path with said rotor and drive shaft.

5. A pump comprising a housing forming a suction chamber, a rotor having one end positioned in said suction chamber, said one end having an axial recess therein, a drive shaft having one end secured in said recess, and a flexible tubular rag guard having one end fixed relative to said housing, the other end of said rag guard fitting around said one end of said rotor whereby said rag guard encloses the portion of said drive shaft in said suction chamber and the connection between said drive shaft and rotor, said rag guard having an annular fold adjacent the first mentioned end thereof to prevent displacement from said rotor, said rotor being rotatable relative to said last mentioned end of said rag guard, and said rotor being movable in a circular path with said one end of the drive shaft and said last mentioned end of said rag guard.

10 6. A pump comprising a housing forming a suction chamber, a rotor having one end positioned in said suction chamber, said one end having an axial recess therein, a drive shaft having one end secured in said recess, and a flexible tubular rag guard having one end fixed relative to said housing, the other end of said rag guard fitting around said one end of said rotor whereby said rag guard encloses the portion of said drive shaft in said suction chamber and the connection between said drive shaft and rotor, said rag guard having an annular fold adjacent the first mentioned end thereof to prevent displacement from said rotor, said rotor being movable in a circular path with said one end of the drive shaft and said last mentioned end of said rag guard, said rag guard having a plurality of apertures too small to permit rags to pass therethrough, said apertures providing passageways for liquid from said suction chamber to equalize the pressure within the space enclosed by said rag guard and the rest of the suction chamber.
